UNITED STATES PATENT OFFICE.

FREDERICK HACKMANN, OF CHICAGO, ILLINOIS.

TRACK LINER.

Application filed August 20, 1923. Serial No. 658,220.

This invention relates to a track liner and particularly to a device which is adapted to be used in railway work for the purpose of aligning the rails and ties so that a train may pass smoothly thereover.

It is an object of the present invention to provide a track liner which is adapted to exert a substantial lateral thrust upon the application of a relatively small force.

It is another object of this invention to provide a track liner which is adapted to be conveniently operated to align track in cramped positions, as for example adjacent platforms, etc.

It is a further object of this invention to provide a device of the class described wherein the thrust bar is laterally slidable and adapted to have a track engaging extension removably connected thereto.

It is a further object of this invention to provide a track liner which may be easily operated under a variety of conditions and which may be economically manufactured.

Other and further important objects of this invention will be apparent from the disclosures in the specification and drawings.

The invention (in a preferred form) is illustrated on the drawings and hereinafter more fully described.

On the drawings:

Figure 1 is a side elevation of a track liner embodying the principles of this invention.

Figure 2 is a fragmentary side elevation, with parts in section, showing the track liner directly applied to align a track.

Figure 3 is a view similar to Figure 2 showing an indirect application of a track liner for use in cramped positions.

Figure 4 is a top plan view of a track liner.

Figure 5 is a front elevation thereof.

Figure 6 is an enlarged fragmentary section, with parts in elevation, on the line 6-6 of Figure 4.

As shown on the drawings:

The reference numeral 1 indicates a metallic base which has integral brackets 2 extending upwardly therefrom and which has an inclined track or guide-way 3 sloping upwardly toward the forward end of the base 1 formed between said brackets 2. Said brackets 2 are reinforced at their forward edges by integral outwardly extending flanges 2^a which terminate at their upper

ends in integral bosses 2^b. Formed on the forward end of the base 1 is an extension 4 which affords a handle by which the device may be carried about and which also affords an extending portion that may be engaged under the flange of a rail as shown in Figure 2. The base 1 is adapted to be anchored relative to a surface on which it is rested by means of lugs 5 and also by means of pairs of movably mounted pins 6 which are loosely engaged through apertures in the base 1 outside of each of the brackets 2 and the upper ends of which are preferably integrally connected by striker portions 7 which may be engaged by an ordinary line bar or similar tool to drive the pins 6 into the ground. In order that the pins 6 may not fall away from the base 1 when the same is carried from place to place they are preferably provided with movable locking pins 8 which prevent said pins 6 from falling through the apertures in the base 1.

Slidably mounted in the track or guide-way 3 between the brackets 2 is a bar 9 which has a groove 10 formed in its outer end to engage the flange of a track 11 as indicated in Figure 2. Said bar 9 has a plurality of notches 12 formed in its upper face, and as clearly indicated in Figure 6, the forward sides of said notches are preferably substantially vertical, and the rearward sides of said notches are inclined. In order to limit the movement of the bar 9 and to prevent the same from dropping away from the base when the device is carried about, grooves 13 are preferably formed in the side faces thereof, said grooves 13 each having engaged therein a headless set screw 14, said set screws 14 being made without heads in order that they may not interfere with the movement of the striker portions 7 above referred to.

Pivottally mounted in a bearing 15 formed between the upper ends of the brackets 2 is a lever 16 which, as indicated in Figures 2, 3 and 4 is cored out at its upper end to receive an ordinary lining bar or similar tool 17. The pivotal mounting of said lever 16 is afforded by integral trunnions 18 which extend from either side thereof and which are flattened to allow of their movement through grooves 19 formed in the inner faces of the brackets 2, as indicated in Figures 4 and 6. The provision of said

grooves 19 makes it possible to rotate the lever 16 in such position that the trunnions 18 may be slid upwardly through said grooves 19, and in order that the lever may 5 normally be prevented from falling away from the base when rotated into such position, removable pins 20 are provided which extend through the brackets 2 and into the grooves 19 near the upper ends thereof. The 10 lower end of the lever 16 is recessed as indicated in Figure 6, and slidably mounted in the recess therein is a latch member 21 which has an integral catch portion 22 thereon that is formed to engage in the grooves 12, 15 the forward face of said catch portion being substantially parallel with the forward face of the lever, while the rear portion of said catch is rounded to permit the same to easily slide over the inclined walls of the grooves 20 12 when the upper end of the lever is tilted forwardly. Said latch member 21 is retained in the recess in the lower end of the lever 16 by means of a pin or handle 23 which is secured in the front face thereof 25 and which extends outwardly through a slot 24 formed in the outer face of the lever and communicating with the recess therein.

It is often necessary that devices of the 30 type under consideration be operated under cramped conditions, as, for example, adjacent loading platforms, depot platforms and the like where it is impossible or impracticable to insert the base 1 and attendant mechanisms in the position relative to the rail 35 11 which is indicated in Figure 2. This invention makes provision for such contingencies by a rail engaging extension 25 which is provided with a hook portion 26 which engages over the outer flange of the 40 rail as indicated in Figure 3. Said extension 25 has a channel formed at its inner end, and formed on the inner end of the side walls of the channel are lugs 27 which engage in grooves 28 formed in the outer sides of 45 the bar 9, said bar 9 being provided with a reduced extension extending beyond said grooves between the ends of the walls of the channel formed at the inner end of the extension 25. By this construction it is 50 possible to removably connect the extension 25 to the outer end of the bar 9 with a secure connection. While this connection is secure, it will be apparent that the same may be quickly made and it will also be apparent 55 that the parts comprising the connecting means may be formed without special machine work. The upper side of the bar 9 is covered by a plate 30 which is integral with the brackets 2 and which has an upward integral extension 31 thereon which forms the rear side of the bearing 15. In order to prevent the lever 16 from being tilted too far rearwardly during normal 60 operation thereof, a removable pin 32 is preferably inserted through registering 65

apertures 33 formed in the brackets 2 in rear of the bearing 15.

The operation of the device of this invention will be obvious from the foregoing description. When it is desired to align 70 a track which is positioned as indicated in Figure 2 so that the flange of the rail 11 is accessible from the outside, the base 1 is placed between ties 34 and the flange of the rail is engaged by the notch 11. The anchoring means 5 are driven into the ground engaging the portion 30 with a suitable tool, and the anchoring pins 6 are subsequently driven into position by engagement of the 75 striker portion 7 thereon in similar manner. 80 After a proper number of devices have been thus positioned, the catch portion 22 on the latch 21 is allowed to drop into one of the notches 12 and the lever 16 is rotated about its pivot point by grasping the bar 17. This 85 serves to move the bar 9 forwardly to shift the rails 11 and ties 34 and thus align the track. Further movement of the track may of course be effected by engaging the catch 90 22 in successive notches 12 and repeating 95 the operation above described.

In case a depot platform 35 or the like prevents the positioning of the device in the manner just described, the same may be positioned as indicated in Figure 3. In this 95 case the extension 25 is engaged under the rail 11 with the hook portion 26 on same extended over the outer flange of said rail. The device is anchored and operated in the manner previously described, in this case 100 the rails and ties being pulled instead of pushed in the shifting movement. It is of course apparent that by the provision of such a removable extension it is possible to 105 operate the device in very cramped positions.

I am aware that numerous details of construction may be varied through a wide range without departing from the principles of this invention, and I therefore do not purpose limiting the patent granted otherwise than necessitated by the prior art.

I claim as my invention:

1. A track liner comprising a base, a track engaging bar movably mounted thereon, pivotally mounted means for operating said 115 bar, a track engaging extension removably secured to said bar and a guide member slidably engaging the lower surfaces of said bar and said extension.

2. A track liner comprising a base, a guide member therein, track engaging means slidably mounted in said guide member, pivotally mounted means for operating said track engaging means, and a track engaging extension removably secured to said track engaging means and slidably in said guide member.

3. A track liner comprising a base, track engaging means movably mounted thereon, and a track engaging extension removably 130

secured to said track engaging means and slidable in substantially the same plane therewith.

4. A track liner comprising a base, an inclined guideway formed thereon, track engaging means slidably mounted in the guideway, and means on the base for operating said track engaging means.

5. A track liner comprising a base, a rearwardly inclined guideway formed thereon, track engaging means slidably mounted in the guideway, and means on the base for operating said track engaging means.

In testimony whereof I have hereunto subscribed my name.

FREDERICK HACKMANN.
